UNITED STATES PATENT OFFICE

WILLIAM H. WOOD, OF SOUTH EUCLID, OHIO

LAMP

Application filed February 26, 1926. Serial No. 90,781.

This invention relates to vehicle headlights and has for its object the provision of an improved reflector designed primarily for use with multi-filament lamp bulbs, which shall be easy to make and polish or repolish and which shall afford an improved distribution and pattern of the light produced; the provision of a reflector which shall produce a beam which changes in position in a predetermined way, with or without change of pattern as may be desired, upon use of one or another filament; the provision of a reflector which exhibits a minimum of sensitiveness to changes in the position of the light source other than a vertical direction. In the following description it should be kept in mind that my improved reflector is equally usable with a single filament lamp bulb and produces a light of maximum lighting efficiency with a minimum of wasted or objectionable rays.

When automobiles first came into use the only known lights were very dim. The speed requirements soon entailed the use of brighter lights, which exhibited the defect of dazzling meeting travelers and leading to accidents. The next step was to dim the light upon meeting another vehicle but this had the disadvantage of reducing the amount of light and until the driver's eyes were able to adjust themselves to the situation he was in partial blindness at the moment of greatest need. Another attempt lay in the employment of a focussed filament for the driving light and an un-focussed filament for the passing light, (either in the same or a different bulb) but these entailed the same difficulty.

More recently it has been suggested to employ two filaments of equal candlepower so located as to cause merely a limited elevation or depression of the beam but without substantial change in its pattern or intensity, but difficulty has been experienced in the provision of a lamp (either by the use of reflectors or lenses or both) which should do this. The specific object of my invention is to accomplish this easily, simply, cheaply and with certainty, either by the reflector alone or by the use of a reflector assisted by a lens; the accomplishment of this specific object also

satisfies the general objects heretofore mentioned.

In the drawings accompanying and forming a part of this application I have shown a preferred physical embodiment of my invention, wherein Fig. 1 is a diagram of the different portions of my improved reflector viewed from in front; Figs. 2, 3, and 4 are axial sectional views corresponding to the lines 2—2, 3—3, and 4—4 respectively of Fig. 1; Fig. 5 is a vertical sectional view of a completed reflector having a double filament lamp bulb therein; and Fig. 6 illustrates the light pattern produced by each filament of the lamp bulb shown in Fig. 5.

The lateral portions of my improved reflector both above and below the central horizontal plane are defined as a surface of revolution of a parabolic generator A about its own axis a—a, which becomes the main reflector axis and in use is supported approximately horizontal (to be strictly accurate it is preferably used with a downward inclination of about 1°, but for most descriptive purposes this can be considered as horizontal).

As a result the horizontal axial section of the reflector is defined by a true parabola as shown in Fig. 3. The portion of the reflector is identified by the little crosses + + in Fig. 1.

The top and bottom median portions are leaned downwardly as compared with such paraboloid surface and are produced by rotating suitable generators about axes which are parallel to the axis a—a but more distant so that these portions have a longer radius of curvature than the paraboloid. The generators employed for defining these top and bottom surfaces are different. That at the top is indicated at B and leaves the parabola A at some point q which must be at the rear of the parameter p, p. This generator B diverges progressively from the parabola A with increasing distance from the vertex of the parabola A, and may itself be considered as a segment of a suitable parabola suitably inclined. For successful use with a double filament lamp the point q must be located a substantial distance rearwardly of

the parameter, and may even approach the vertex. This generator is rotated about an axis $b-b$ which is parallel to and below the axis $a-a$. I have had good success locating this axis $b-b$ at the parametral circle although this particular distance is not significant and may be either increased or decreased according to the width of the diffused light beam desired. The surface of revolution B thus defined lies wholly inside of and beneath the paraboloid surface A (See Fig. 2) and is identified by the small circles $o\ o$ in Fig. 1. This surface extends to symmetrical points on opposite sides of the vertical plane and tends to meet the paraboloid surface by curved lines indicated generally at r, r . In practice, however, this merging is preferably effected by some transition-surfaces, identified by s, s , and t, t , and one convenient way of producing such transition surfaces is to employ generators intermediate between A and B and revolve the same about axes angularly displaced from b around the parametral circle or such other distance as may be chosen. I have shown two transitional surfaces between the vertical and horizontal regions, but more or less can be employed. In fact the smoother and more nearly uniform the surfaces blend together the better is the reflector. In practice the lines r, r , etc. ought not to be apparent.

The generator employed at the bottom is indicated at C and preferably conforms substantially to a parabola whose axis c, c is inclined downwardly as compared with the axis a, a . For certain practical reasons I prefer that the focal length of the parabola C be slightly less than that of the parabola A, e. g. in the proportion of $1\frac{1}{2}$ in. to $1\frac{7}{8}$ in. and to locate the focal point f' of the parabola C $\frac{1}{8}$ in. directly below the focal point f of the parabola A. This means that the vertex of C is displaced inside of the vertex of A and also that C is located inside of A at their (substantially) common parameter, but owing to the inclination of its axis it leans downwardly faster than the curve A at equivalent points. This generator, C, is revolved about an axis c', c' , which is parallel to the axis $a-a$ and above the same, in this case being located on the parametral circle. As a consequence this lower median portion exhibits a smaller transverse curvature than the paraboloid but tends to intersect the paraboloid surface along lines u, u located symmetrically upon opposite sides of the vertical plane. The surface is identified by v, v in Fig. 1, and its margins are merged into the paraboloid surface by transitional surfaces w, w , similar to those at s, t , and produced in an equivalent manner, so that the lines u, u are preferably obliterated.

65 A sectional view on a diagonal such as 4-4

in Fig. 1 cuts across several such surfaces as indicated in Fig. 4.

In practice these curvatures are actually produced as surfaces of revolution on a metal punch which is then impressed in sheet metal forming a unitary reflector illustrated in Fig. 5. In order to accommodate the lamp socket sleeve E a circular flat spot is produced at the tip of the punch which produces a flat heel L which facilitates the attachment 70 of the sleeve and also merges the offset apices of the surfaces A and C. This sleeve E is preferably coaxial with $a-a$, and the bulb G is coaxial with the sleeve. When this bulb contains two filaments M, N, located one 75 above the other the following features of operation are exhibited.

It is obvious that one or the other or both of the filaments must be vertically displaced from the focal point of A, and it makes little 80 difference which condition exists in case the reflector be properly adjusted thereto. It is easily demonstrated that if the reflector were truly paraboloid any elevation of the light source above the focal point will tend to 85 throw downwardly all rays reflected near the vertex and throw upwardly all rays reflected near the mouth, while those rays which are reflected at the parameter change their position not at all; but this condition exists 90 only in and near the vertical plane. At the horizontal plane the only effect produced by raising the light source is to change very 95 slightly the angle of incidence and the result in every case, all around the reflector, and 100 equally behind as before the parameter, is to depress the reflected rays. The amount of this depressing is greatest at the sides of the reflector since here the angle of incidence is changed the most; at points nearest the vertical plane the elevation influences the reflected beam chiefly by parabola action; nearer the horizontal it is the angle of incidence 105 which controls the reflected beam; and at points between the two effects merge into each 110 other.

It should be noted also that the action differs at opposite sides of the parameter. At the rear of the parameter all portions, both vertical and lateral, tend to throw the beam downward as the source is raised, and the parabolic effect in the vertical plane is approximately the same as the angle of incidence effect in the horizontal plane (so long as one remains at a sufficient distance from the parameter) with the result that the beam reflected from most of the heel portion moves as a unit. But in front of the parameter it is only those portions at the horizontal margin which move with the beam from the heel section; at points removed from the horizontal the action is decreased and at points approaching the vertical the action is reversed. Also the greater is the distance in front of the parameter the greater becomes 115 120 125 130

the parabolic action as compared with the simple reflective action.

All the description of the last two paragraphs is based upon the behavior of a simple paraboloid and shows how a simple displacement of the light source vertically of the axis gives rise to a number of different actions at various parts of the reflector with a marked change in the light pattern.

10 By the construction heretofore described I remove those parts of the paraboloid which normally produce the contradictory and confusing effects last described. All portions of the reflector marked ++ remain in concentrating relation with the light source at all times, and any elevation or depression of the light source as by change from M to N serves merely to elevate or depress the concentrated portion H of the light beam shown

15 in Fig. 6. The median portions of the reflector o, o and v, v, both above and below, which normally would move oppositely to the main beam are, by the reduction of lateral curvature, spread sideways, and by the leaning 20 position depressed, so as to illuminate the P and Q points shown in Fig. 6. The sensitivity of these regions to parabolic action 25 may be overcome if desired by balancing them against each other. It will be noted that a part of o, o and a part of v, v is behind 30 the parameter as well as in front. This is adopted for two reasons; first because it is necessary to modify the paraboloid at and immediately behind the parameter since the 35 parabolic effect produced by elevating or depressing the light source is zero at this point whereas it was desired to cause the beam H to move as a whole; the second reason, and the one which determines how far back of the 40 parameter to carry these points is as follows:

The portions o, o and v, v are essentially parabolic and include their parameters so that their front and rear ends exhibit an opposite effect upon the light beam as the light 45 source is lowered or raised. Accordingly upon any given vertical movement of the light source the effect of one end of each of these median portions is to tend to counteract the effect produced by the other end, and the 50 total resultant effect depends upon the relative amount of light falling on those ends. It will be remembered that the light from these regions is that which illuminates the points p and Q in Fig. 6. With the arrangement shown in those views the result of changing from M to N or vice versa is to shift the portion H of the beam about 2° while shifting the Q points about 1° in the same direction and this is a very desirable arrangement since it 55 drops the intense beam out of the way when meeting other vehicles while retaining the lateral portions as a passing light, these being already too low to produce dazzle. It is easy, however, either to increase or to decrease this 60 movement of the Q points. Thus one way to

increase the movement is to increase the proportion of the median sections behind the parameter, as by moving point q nearer the vertex or by narrowing the portions in front of the parameter; while an opposite mode of treatment (combined if desired with a slight change in angle or character of curve) can be caused to keep these points substantially still, only the intense beam being moved. It thus becomes possible, with a very small change in shapes or dimensions, to produce exactly the character and behavior of light beam which may be desired.

In explanation of Fig. 6 it may be stated that the location of the points and their respective illumination by my improved reflector is as follows, the apparent candle-power being given:

Point	Location	Intensity with lower filament	85
AP	Straight ahead	5000 apparent C. P.	
BP	1° down	25000 apparent C. P.	
CP	1° up	800 apparent C. P.	
DP	1° up 4° out	200 apparent C. P.	
PP	1½° down 3° out	8000 apparent C. P.	90
QP	3° down 6° out	3000 apparent C. P.	

The two filaments were of equal candle-power, rated at 21 each. The central most intense beam is derived from the lateral margins, the beam denominated J from portions of the heel removed from the lateral margins, and the portion K from the top and bottom median portions. C and D points are lighted by the flat portion L at the heel which produces a diffused illumination additional to that shown in Fig. 6.

In case it be desired to spread the light further laterally a vertically fluted or corrugated glass may be employed, or an incandescent lamp used which has a wider V or bar shaped filament, or other known expedients employed such as "flattening" of striating the reflector in vertical zones. It is also within my invention to use my improved reflector with the usual single filament bulb and the resulting beam corresponds to one or the other of the beams herein described or shares their characteristics according as the filament is located in the reflector. An intermediate position of the filament is best, however, when only a single filament is used, since the reflector is then peculiarly insensitive to the location of the filament and it becomes safe to employ a fixed socket without adjustment provisions.

It will be understood that a great many changes in detail and appearance can be made within the scope of my invention.

Having thus described my invention what I claim is:

1. In a vehicle headlight, a reflector having at each side a portion extending both above and below the horizontal plane and from the heel portion substantially to the for-

- ward edge thereof defined by a single paraboloid formed about a substantially horizontal axis and having its portions at and upon each side of the vertical axial section leaned downwardly as compared to said first named paraboloid surface at corresponding points, said last named portions having a transverse curvature which is less than would be produced by rotation about the paraboloid axis.
10. 2. In a vehicle headlight, a reflector having its lateral portions defined by a parabolic generator revolved about an approximately horizontal axis, and having its upper median surface defined by revolving a second generator about an axis which is parallel to and below said first axis, said second generator being everywhere leaned downwardly more than said paraboloid surface at equivalent points and progressively diverging from said 15 paraboloid surface, with increasing distance from the vertex, said reflector having its lower median surface produced by rotating a third generator about an axis which is parallel to and above such first axis, said third 20 generator consisting of a parabola whose axis is inclined downwardly as regards the first named axis, said upper and lower median surfaces merging into said paraboloid surface at symmetrical points on opposite sides 25 of the vertical plane.
3. In a vehicle headlight, a reflector having lateral portions which are substantially parabolic, and having median portions both above and below the axis which are parabolic 30 to a focal point which is located in the same vertical axial plane with the focal point of the first named paraboloid, the portions of said reflector lying in the vertical plane behind the focal plane and below the axis being 35 located in front of the surface of said first paraboloid and those portions lying in the vertical plane and above the axis and in front of the focal plane being located below said first paraboloid surface, portions of said reflector adjacent to the vertical axial plane 40 having a smaller curvature in a horizontal direction than corresponds to a surface of revolution about either parabolic axis.
4. In a vehicle-headlight, in combination a reflector having its two lateral portions at 45 and near the horizontal plane and extending to its forward edge defined substantially by segments of a single paraboloid having a substantially horizontal axis, the portions of said reflector at and near the vertical axial plane at and forward of the focal plane having a smaller curvature in a lateral direction and a greater downward inclination in a fore and aft direction than is exhibited by said 50 first named paraboloid at equivalent points, and a lamp bulb having two independently usable concentrated filaments located one above the other and intersected by the same vertical line which passes through the focal 55 point of said paraboloid.
5. In a headlight, a reflector having at each side and extending both above and below the horizontal plane, a surface whose boundaries conform to a single paraboloid surface whose axis is substantially horizontal, the portions of said reflector located 45° from the horizontal plane and forward of the focal plane being located below said paraboloid surface, and the portions of said reflector located
